UNITED STATES PATENT OFFICE.

DAMIAN KALETSAI, ELIAS BELLAS, AND ABRAHAM BRONSTEIN, OF NEW YORK, N. Y.

SYSTEM OF FUR-GARMENT MAKING.

Application filed October 8, 1921. Serial No. 506,316.

To all whom it may concern:

Be it known that we, DAMIAN KALETSAI, ELIAS BELLAS, and ABRAHAM BRONSTEIN, the first two inventors subjects of the King of 5 Greece and the last citizen of the United States, each residing at New York, in the county of New York and State of New York, have invented certain new and useful Improvements in Systems of Fur-Garment 10 Making, of which the following is a specification.

This invention relates to a method of making fur coats, having more particular reference to the making of coats in which 15 a cheaper fur is dyed to simulate a more expensive fur.

The invention has primarily for its object to enable garments to be produced at the lowest possible cost, a more specific object 20 being to enable damaged skins or small pieces to be economically handled.

For further comprehension of the invention, and of the objects and advantages thereof, reference will be had to the following description and accompanying drawing, and to the appended claim in which the various novel features of the invention are more particularly set forth.

The figure of the drawing is a view showing the pattern in which the skins are sewed together prior to clipping and dyeing.

The invention is designed more particularly for use in the production of imitation seal coats, the cheaper quality of coats, 35 known as sealene coats, being commonly produced from the skins of French, Australian or New Zealand rabbits, and the better quality, simulating Hudson seal, being made from the skins of muskrats.

40 Heretofore, in making fur coats of this type, the skins have been first dyed and then clipped and then sewed together to proper pattern. This method has been open to several disadvantages in that the individual handling of each skin in dyeing and clipping involved considerable expense and made the utilization of small pieces, or of badly torn or damaged skins commercially impracticable.

50 In making fur garments according to our

improved method the skins are first sewed together to the proper pattern such as shown in the drawing at 10, the seam lines being indicated at 11, and badly torn skins or small pieces may be readily utilized since 55 there is no individual handling of the same except in the sewing of the skins together.

The joined skins are then clipped to give the fur an even thickness throughout the garment, this clipping being accomplished 60 with much greater facility than when following the old method.

The joined and clipped skins are then subjected to the proper dyeing operation to give them the desired appearance, the whole body 65 of the coat being handled as a single unit in this operation.

The patterned skins may then be cut along the dotted lines 12 to form the coat, or they may be cut into any number of pieces of 70 such shape as may be desired.

As will be apparent, with our improved method of making coats of this type a considerable saving in expenses is effected, while skins that otherwise would be of no use, are 75 utilized with advantage.

Having thus described our invention what we claim as new and desire to protect by Letters Patent of the United States is as follows:

80 A method of making wearing apparel consisting of sewing together the adjacent edges of animal skins shaped as when they are taken from the animal, utilizing small pieces of such skins and other pieces of badly torn 85 skins to fill out the spaces between the larger skins, clipping or otherwise treating the combined skins so that the fur shall be of even length throughout the entire article, dyeing the entire article, and cutting or 90 otherwise determining the shape of the entire composite article so that it will conform to a definite shape desired in the manufacture of a certain article of wearing apparel.

95 In testimony whereof we have affixed our signatures.

DAMIAN KALETSAI.
ELIAS BELLAS.
AL BRONSTEIN.
